SCAFFOLD BRACKET

Carl W. Almgren, 6167 N. Moody, Chicago, Ill.
Filed Aug. 8, 1962, Ser. No. 215,614
3 Claims. (Cl. 182—87)

The present invention relates to the support of scaffolding from concrete wall forms. The scaffolding support of this invention is rugged, easily constructed and quickly dismantled and can be used repeatedly.

The concrete wall forms concerned in this invention are of the type wherein the opposed form walls include rectangular panels assembled in edge-to-edge relationship with the wet concrete being poured into the space defined by the walls. The panels commonly employed consist of plywood against which the wet concrete lies, and a strengthening and rigidifying framework is applied to the outer surface of the panels to maintain proper alignment of the wall form as the wet concrete is being poured and during its drying process. This rigidifying framework usually consists of vertical members applied both at the margins of the panels and at intermediate distances between the edges of the panels. Where walls are of considerable length it is customary to further reinforce the wall forms with heavy stiffening members or walers which are horizontally disposed in a transverse relationship to and bear against the outer surface of the vertical members. Usually the two walls are tied or connected together with tie rods to maintain a proper distance between the inner plywood faces of the two wall forms. These tie rods generally are adapted with a head or enlargement at each end and have washers or spacers disposed a distance from the ends with bosses protruding from the tie rods to prevent distal movement of the washers.

The present invention has particular reference to concrete wall forms which embody either or both the walers and the tie rods.

One object of this invention is to provide a new and novel means to support a scaffold structure on the outside surface of form walls, on which men and material may easily traverse the length of the form walls at various levels of height and on which materials may rest or be suspended.

Another object of this invention is to provide a scaffold bracket which is simple to use and is easily mounted and dismantled.

Another object of this invention is to provide a scaffold bracket which can be secured to the form walls by attaching to components generally used in concrete form wall construction.

Another object of this invention is to provide a scaffold bracket which can be secured to the form wall by simple engagement with horizontal stiffening members or walers on the outside surface of the wall.

Another object of this invention is to provide a scaffold bracket which can be secured to the form wall by simply engagement with tie rods extending from the outer surface of the wall.

Yet another object of this invention is to provide a scaffold bracket which is simple in construction, has no moving parts and which is convenient to store when not in use.

These and other objects of the invention will appear from time to time as the following specification proceeds and with reference being made to the accompanying single page of drawings wherein:

FIGURE 1 is a perspective view of the scaffold bracket;

FIGURE 2 is a rear view of the scaffold bracket showing the slots on the back side of the U-flanges;

FIGURE 3 is a side view of a scaffold bracket showing U-flanges extending over and supported by a pair

2

of walers, and a scaffold structure formed on the scaffold bracket; and

FIGURE 4 is a fragmentary side view of a scaffold showing the U-flanges of the scaffold bracket suspended from tie rods which protrude through the form wall, the tie rods being inserted into the slots in the backside of the U-flanges.

In the embodiment of the invention illustrated in FIGURES 1 and 2, I have shown a scaffold bracket 1 having a vertical member 2 which is preferably made from rigid channel iron. A U-flange 3 is shown extending from the back or flat side of the vertical member 2 and welded or otherwise secured thereto. The U-flange 3 is shown in an inverted U position in relation to the vertical member 2 and forms a hook member for extending over a waler. In the illustrated form of the invention the space between the inner surface of the inner side 4 and the inner surface of the outer side 5 of the U-flange 3 is slightly larger than the smaller dimension of a standard wooden 2" x 4", although it is understood that this distance could be made greater or smaller to accommodate engagement with walers of a different thickness. The height of the inner and outer sides as shown is approximately two-thirds the larger dimension of a standard wooden 2" x 4", although this dimension could also be modified within the scope of this invention.

In its preferable form, U-flange 3 is of unitary construction and made from rigid channel iron or other suitable material. A slot 6 is formed in the outer side 5 of the U-flange 3. Preferably, this slot is wider in its horizontal dimension than the shank of a tie rod but is less than the head or enlargement at the end of a tie rod. The depth of the slot in its preferable form would be more than half the vertical dimension of the U-flange 3 and preferably terminating below the topside 19 of the U-flange, as shown. A multiplicity of nail holes 7 are formed in the topside 8 of the U-flange 3. In the form illustrated I have shown two nail holes positioned marginally on either side of the topside of the U-flange. Being positioned thusly, nails can be driven through the holes without interference between the vertical member 2 and the head of a hammer used to strike the nail. However, other locations of the nail holes could be used.

Two angle flanges 9 and 10 are shown at the lower extremity of the vertical member 2. The flanges are rigidly connected to the vertical member preferably by means of a weld to the outer edges of the parallel sides 11 and 12 of the vertical member 2. In the preferable form which is illustrated the angle flanges have a three sided configuration and are made of heavy metal although other suitable material can be used. Bolt holes 13 and 14 as shown form holes through each of the two angle flanges. These bolt holes are concentric, having a common axis extending transverse to the angle flanges and positioned approximately in the center of the angle flanges, thereby permitting the insertion of a bolt (not shown) through the aligned bore holes without interference.

A second U-flange 15 is connected by a weld or other rigid means to the upper extremity of the vertical member 2 and forms a second hook member for extending over a waler. This U-flange is of the same unitary construction and has the same configuration as U-flange 3, being embodied with a slot 16 in the outer side 17 and nail holes 18 in the topside 19 of the U-flange. The slot and nail holes are sized and positioned in the same relation to U-flange 15 as the slot 6 and nail holes 7 bear to the U-flange 3.

A brace holder 20 is shown at the upper end 21 of the vertical member 2. This brace holder is preferably of unitary construction formed from heavy rigid metal although other suitable material may be used. The outer sides 22 and 23 of the brace holder extend in a horizontal

plane from the outer edges of the parallel sides 11 and 12 of the vertical member 2 and the outer side 17 of the U-flange 15, and the overall width of the brace holder is equal to the width of the vertical member.

Bolt holes 24 and 25 are shown in the outer sides 23 and 24 of the U-flange 15. Each of the two bolt holes in the outer sides 23 and 24 of the U-flange 15 are concentrically disposed and in registry with a corresponding bolt hole in the opposite outer side, thereby permitting the insertion of a bolt (not shown) through the matching aligned bolt holes without interference.

Referring to FIGURE 3, a fragmentary cross-section of a conventional wall form is shown, wherein plywood paneling 26 comprises the surface of the wall against which the wet concrete makes contact. A vertical stud 27 is secured to the outer surface of the plywood paneling to reinforce and rigidify the paneling. In the usual construction of a concrete wall form such vertical studs are placed around the entire circumference of the wall at predetermined intervals. Normally the vertical studding used is standard wooden 2" x 4". To further strengthen the wall form and preclude bending and bulging under the weight of the wet concrete, walers 28 are horizontally disposed transverse to and in abutting engagement with the vertical studding. Usually, walers are spaced at predetermined intervals from the bottom to the top of the wall form, and generally take the form of a single standard wooden 2" x 4" or two 2" x 4" separated by a spacer block (not shown). To prevent the two opposed walls of a concrete wall form from separating from each other beyond their intended distance when the concrete is poured, tie rods 29 are generally employed which extend through the plywood paneling and are often rigidly fastened by a clamp (not shown) or other device to the walers of each of the two opposed wall forms. Washers 30 are usually placed on the shanks of the tie rods and distally retained on the shanks by a small boss (not shown) on the shank. Tie rods are generally formed with an enlargement or head 31 at both ends of the tie rod shank.

In the illustrated form of my invention shown in FIGURE 3, a scaffold bracket 1 is rigidly suspended along the outside of the form wall by engagement with walers 28. In suspending the scaffold bracket in this manner the U-flanges 3 and 15 are slipped down over the walers 28 whereby the top of the walers are in abutting engagement with the top side of the U-flanges. An angle brace 32 is disposed between the angle flanges 9. This angle brace, in its preferred form, is a standard wooden 2" x 4" and has a bolt hole (not shown) concentrically aligned and in registry with the bolt holes 13 and 14 of the angle flanges. A bolt 33 is shown inserted in the bore defined by the bore holes of the angle flanges and angle brace. A threaded nut (not shown) is secured to the opposite end of the bolt 33 thereby forming a fixed connection between the angle brace and the angle flanges. A flat brace 34 is disposed in the space defined by the two outer sides 22 and 23 of the brace holder 20. In its preferable form, this flat brace is a standard wooden 2" x 6" having two bore holes arranged concentrically with the bolt holes 24 and 25 of the brace holder 20. Bolts 35 are shown inserted in the bore defined by the bore holes of the brace holder and the flat brace. Threaded nuts (not shown) are secured to the opposite ends of the bolts 35 thereby forming a fixed connection between the brace holder 20 and the flat brace 34. One side of the outer end of the flat brace 34 overlaps and is in engagement with one side of the upper end of the angle brace 32. In this form of the invention nails 36 are used to fixedly connect the adjacent portions of the angle brace and flat brace. However, these two braces could be connected with a bolt or other suitable means. As illustrated in FIGURE 1, nail holes 7 and 18 are formed in the top sides 8 and 19 of the U-flanges 3 and 15. When the invention is shown as used in FIGURE 4, nails may be driven through the nail holes into the walers 28 thereby

providing a positive means of preventing movement of the scaffold bracket along the waler.

In FIGURE 4 a second form of my invention is shown wherein the scaffold bracket 1 is rigidly suspended along the outside of the form wall by engagement with the tie rods 29. In suspending the scaffold bracket in this manner the slots 6 and 16 of the U-flanges 3 and 15 are slipped down over the tie rods 29 behind the tie rod heads 31. The scaffold bracket is moved vertically downwardly until the shank of the tie rod is in abutting engagement with the top of the slots in the U-flanges.

Scaffold planks 37 are shown in FIGURES 3 and 4 resting on top of the flat brace 34. These planks are laid horizontally and, depending on the length of the plank, rest on two or more flat braces. Preferably, a number of wooden angle braces 32 and flat braces 34 would be cut to size and properly drilled for bolt holes.

Although FIGURES 1 and 2 disclose my invention comprising vertical member 2 as an integral part thereof, it is apparent that the major portion of vertical member 2 could readily consist of a wooden 2" x 4" or the like (not shown). In this form of my invention the vertical member 2 as illustrated would be horizontally severed at the bottom of the upper U-flange 15 and at the top of the lower U-flange 3, thereby providing two separate U-flange assemblies which could be vertically aligned and connected by means of a 2" x 4". This form of my invention would be preferable where the vertical distance between walers or tie-rods varies and it would not be practical to permanently fix the vertical distance between U-flanges.

It is to be noted from the foregoing that a rugged, easily constructed and quickly dismantled form wall scaffold has been provided and that the simple, easy construction has been attained by the use of the particular scaffold bracket comprising the present invention. By using the same pre-cut and drilled braces over and over again, a scaffold can be constructed repeatedly with a minimum of time and expenditure.

While I have herein shown and described one form in which my invention may be embodied, it may readily be understood that various modifications and variations in the invention may be attained without departing from the spirit and scope of the novel concepts thereof as defined by the claims appended hereto.

I claim as my invention:

1. A scaffold support structure for use with a concrete wall form having a panel, a plurality of spaced vertical studs secured to and rigidifying said panel, and a plurality of spaced horizontal tie rods having an enlargement or head at each end thereof and extending through said panels which comprises,

a vertical member,
a brace holder member secured to the upper end of said vertical member,
a horizontal brace member,
means to fixedly connect said horizontal brace member to said brace holder member,
an angle brace connected to the lower end of said vertical member and connected at its upper end to said horizontal brace member,
and upper and lower U-flanges secured at the upper and lower ends of said vertical member each positioned to form a hook for seating over a waler and each having an upper horizontal plate portion for resting on the top of the waler and a vertical outer plate portion for hooking behind the waler,

said outer plate portions having vertical slots extending upwardly from the lower edge thereof with the upper end of the slot having a downwardly facing surface for engaging on the rod so that said slot slides over a headed tie rod with the tie rod head engaging the inner surface of the vertical plate portion at the sides of the slot.

2. A scaffold bracket in accordance with claim 1 including a plurality of horizontally disposed scaffold planks

resting movably on the upper surface of said horizontal brace member and wherein the vertical slots terminate below said horizontal plate portion so that the tie rod head engages the inner surface of the vertical plate portion above the slot.

3. A scaffold bracket adapted for application to a concrete wall form having a panel wall, vertical studs attached to and rigidifying the panel wall, a plurality of spaced-apart horizontal walers attached to the studs, and tie rods extending through the panel wall, said scaffold bracket comprising,

a vertical member,

a brace holder attached to the top end of the vertical member and having a pair of spaced parallel outer faces extending vertically upwardly to receive therebetween one end of a horizontal brace member, a plurality of aligned bolt holes formed in the outer faces of the brace holder for receiving respectively a bolt for securing the horizontal brace member to the brace holder,

a pair of parallel spaced angle flanges secured to the lower end of the vertical member on one side thereof for receiving one end of an angle brace therebetween, bolt holes formed in said angle flanges and in alignment with each other for receiving a bolt to secure the angle brace to the angle flanges,

a pair of vertically aligned U-flanges attached respectively to a side opposite said one side of the vertical member at each end thereof and opening downwardly to extend respectively over a pair of walers,

the said U-flanges having downwardly facing planar surfaces for simultaneously engaging the upper sides of a pair of walers to jointly bear the vertical load of the bracket, and

an elongated vertical slot formed respectively in each of the U-flanges on the side thereof opposite the vertical member and opening to the bottom of the flanges,

said slots being arranged in vertical alignment and having upper edges for simultaneously engaging the shanks of a pair of tie rods to jointly bear the vertical load of the bracket.
